APPARATUS AND METHOD FOR DRYING
SOLID MATERIALJohn E. Peirce, Arlington, N. J., assignor to Allied
Chemical & Dye Corporation, a corporation of
New York

Application July 14, 1945, Serial No. 605,142

3 Claims. (CL 34—137)

1

This invention relates to apparatus and method for treating solid material with a gas, at least some of which material exists as dust when in the treated condition.

The present improvements may be exemplified in connection with construction and operation of a rotary drum used to effect the final drying of salts such as anhydrous bisulfite of soda, trisodium phosphate, sodium hyposulfite, and sodium bifluoride. In several processes in the chemical industry, materials of the nature indicated are preliminarily dried, e. g. dewatered or separated from the mother liquor as by a centrifuge, and there results a salt containing say 3-10% moisture which must be removed before the material is ready for packaging. Final drying is commonly effected by means of a rotary drum and a suitable drying gas. In the operation of apparatus of this type, the material to be dried is fed into one end of the drum arranged so that the material passes thru the drum to the opposite or material outlet end. A drying gas such as heated and filtered air or a heated inert gas such as carbon dioxide, depending upon the particular nature of the operation at hand, is charged into the material outlet end of the drum and flowed thru the drum countercurrent to movement of the material. Because of their damp condition as fed into the drum, such materials present no particular dusting problem in that portion of the drying zone at and near the material inlet-gas outlet end of the dryer. However, as the material is gradually dried, dusting proportionately increases, and in the immediate vicinity of the material discharge end, a substantial amount of the material exists in dust form. Because of dusting, depending largely upon the diameter of the dryer, it is necessary to supply the treating gas thereto in such a way that the gas stream passing thru the dryer has a velocity insufficient to entrain an appreciable dust load, this requirement being imposed so as to avoid sweeping dust, constituting an appreciable portion of the dry product, out of the dryer along with the spent gaseous drying agent. Thus for a dryer of given design, the velocity of the treating gas passing thru the drying chamber must be held below or at not more than a given maximum.

In the construction of dryers of the kind under consideration, the treating or drying gas is usually fed into the drum from a gas bustle or vestibule communicating with the source of gaseous drying agent. As previously stated, the atmosphere at the solid material discharge-drying gas inlet end of the dryer is substantially dust-laden. Because of this condition, and the fact that the dryer proper is rotary and the gas vestibule is fixed, in the prior practice it has been customary to attempt to provide gas-tight joints at the connection between the fixed gas bustle

and the rotary drum. Principally because of appreciable eccentric and axial movement of the rotary drum, resulting from wear and tear and maladjustment of the rotary drum on its supporting rollers and driving gears, it is difficult and often impossible to provide a gas and dust-tight joint between the rotary drum and the fixed gas inlet. Hence, to avoid dusting at this joint it has been the practice to operate the apparatus as a whole in such a way as to maintain a slight negative gas pressure at the material outlet-gas inlet end of the dryer. Such a procedure requires the use not only of a blower to supply gas to the gas inlet end of the dryer but also an additional suction fan in the tail gas line of the dryer, the operation of which fan must be carefully adjusted in order to maintain the desired negative pressure at the material discharge-gas inlet end of the dryer. Often, it is necessary to effect drying by means of an inert gas to avoid oxidation of the material being dried. In this situation, when operating in accordance with the prior practice, i. e. maintaining a negative pressure at the material outlet end of the drum, it is not possible to avoid drawing in atmospheric air thru the joint between the rotary drum and the fixed gas inlet. Further, the atmosphere in many chemical plants contains impurities which are sucked into the dryer and cause contamination of the product being dried.

This invention aims to provide a system by means of which the foregoing difficulties are eliminated. The invention, its further objects and advantages may be understood from the following description taken in connection with the accompanying drawing, in which Fig. 1 is a longitudinal vertical section of the improved apparatus, and Fig. 2 is a transverse section on the line 2—2 of Fig. 1.

Referring to the drawing, 10 indicates a horizontal cylindrical drum providing an elongated drying chamber 11. The drum is mounted for rotation on rollers 12 and tracks 13, and is equipped with suitable driving gear not shown associated with a source of power. Damp material to be dried may be fed continuously by a star feeder 15 into a chamber 16 having at the bottom a ribbon conveyor 17. Introduction of material into chamber 16 may be such that the level of material is maintained at about or below the axis of the conveyor 17 so as to provide a free space thru which spent drying gas enters chamber 16 for discharge from the apparatus thru outlet 21. The drum is pitched slightly toward the gas inlet end which pitch in conjunction with longitudinal flights 22 serves to move the material thru chamber 11.

A source of gaseous drying medium 23 is connected to the suction side of a blower 24 which forces the gas successively thru a suitable purifier

26 and a heater 27, the discharge pipe 28 of which is provided with a valve 29 and opens into the fixed gas inlet chamber or vestibule indicated generally by 30.

According to the present invention, it is not necessary to attempt to provide a gas and dust-tight joint at the connection between the fixed gas chamber 30 and the rotary drum 10. The construction and operation afforded are such, notwithstanding the requirement of maintaining in the drying chamber 11 a relatively low gas velocity, as to prevent the presence of dust at the gas inlet opening of the drum and at the connection between the drum and the fixed gas inlet chamber. On the side adjacent the rotary drum, chamber 30 is provided with a circular cut-out 32 having a diameter appreciably greater than the outside diameter of the drum neck 33 which projects into chamber 30 and forms a gas inlet opening 34 for the drum. If desired neck 33 may be provided with an outwardly projecting flange 35. As shown on the drawing, the relation of drum neck 33 and flange 35 on the one hand and circular cut-out 32 on the other is such as to permit appreciable eccentric and axial movement of the drum neck without a metal-to-metal contact and thus affords a non-gas-tight joint connection between the drum and the gas chamber.

In accordance with the invention, the area of the gas inlet opening 34 of the drum is chosen, relative to the cross-sectional area of drying chamber 11 and a maximum permissible gas velocity thru the latter, so that there is created in the gas stream passing thru inlet opening 34 a gas velocity high enough to prevent the presence of dust in the immediate vicinity of neck 34 and the connection thereof with the gas chamber. For this purpose, the material outlet end of the drum is provided with a section 38 connecting the end of the drum to the drum neck 33. While section 38 may be cylindrical and coextensive with neck 33, in which case section 38 connects with the vertical end wall 39 of the drum at a right angle, preferably section 38 is conical and approximately of the configuration shown on the drawing. The conical design of section 38 along with the restricted cross-sectional area of drum throat 33 provide a Venturi tube effect which facilitates maintenance at the gas inlet end of the drum of a relatively high gas velocity. It has been found that, in order to create in the gas stream entering the drum a gas velocity high enough to prevent the presence of dust in that vicinity, the cross-sectional area of the drum throat 33 should not be more than about one third the cross-sectional area of drying chamber 11. Further, when using a conical connecting section 38, to create the most desirable Venturi tube effect and secure the best results, it has been found that the area of the circle formed by the intersection of connection 38 and drum wall 39 should be not more than half the cross-sectional area of chamber 11, and that the axial length of section 38 should be equal to at least half the diameter of opening 34.

Another feature of the invention provides for removal of the dry material from the drum in such a way that the material being discharged is out of contact with the gas stream entering thru opening 34. This objective is accomplished by a conveyor the tube 45 of which is supported in the position shown on the drawing by a suitable bracket 46 and the end wall 47 of gas chamber 30. Tube 45 houses a screw 49 driven by a motor

50 and opens at the discharge end into an elevator conduit 51 or other receptacle. The closed portion of the tube 45 extends into drying chamber 11 far enough so that material being discharged by conveyor 49 is out of contact with gas in the zone of high gas velocity. The inner end of tube 45 is provided with an open top trough 54, the design of such trough and of flights 22 being such that, during normal rotation of the drum, those portions of flights 22 adjacent the solid material outlet end of the drum keep trough 54 filled with dry material.

Assuming use of air as the drying agent, operation is as follows: Air is drawn into the system by blower 24 and passed successively thru a suitable filter or purifier 26 and a heater 27 in which the air is heated to the desired drying temperature. Valve 29 in pipe 28 is adjusted so as to maintain heated air in the gas inlet chamber 30 under such a positive pressure that the velocity of the gas stream passing thru drying chamber 11 does not exceed or is less than the maximum permissible value, specific velocity being dependent upon the cross-sectional area of chamber 11 and the nature of the material being dried. By the construction described, there is thus created in the vicinity of the drum throat and of the connection between the same and the fixed gas chamber 30, a gas velocity which is high enough to keep dust back in the drying chamber and well away from the gas inlet zone formed by the conical section 38, drum throat 33 and the non-gas-tight connection between the throat and gas inlet chamber 30. The positive pressure existing in chamber 30 maintains a small outflow of gas at the connection between the rotary drum and the fixed gas chamber and prevents ingress of atmospheric air.

Following is an example of operation in which 40 the material dried was anhydrous bisulfite of soda containing about 5% by weight of water as fed into the rotary drum. The length of the cylindrical portion of the drum was 40 feet. The axial length of section 38 was 18 in., and the 45 inside diameter of drum throat 33 was 24 inches. The cross-sectional areas of drying chamber 11, of the circle of intersection of end wall 39 and conical connection 38, and of gas inlet opening 34 were 19.6, 7, and 3.1 square feet respectively. 50 Air was cleaned in purifier 26 by passing thru glass wool and cloth filter, and heated in heater 27 to an initial drying temperature of 95° C. Blower 24 and valve 29 were adjusted so as to maintain the gas in chamber 30 at a positive 55 pressure of 0.2 in. (water). This pressure created an average gas velocity in the cylindrical section of drying chamber 11 of about 120 feet per minute, which gas velocity was low enough to avoid substantial entrainment of dust in the 60 spent gas discharged from the dryer. Under these conditions, the solid material was dried at a rate of 1.5 tons per hour, and there was no discernable leakage of dust at the non-gas-tight connection between the drum and the fixed gas chamber 30.

I claim:

1. Apparatus for treating solid material at least some of which exists as dust when in the treated condition, which apparatus comprises a 70 rotary drum forming a treating chamber and having a material inlet-gas outlet end and an oppositely disposed material discharge-gas inlet end, means for introducing solid material to be treated into said material inlet end of said chamber, means for moving the material thru said

chamber to said gas inlet end, an annular wall fixed at its outer periphery to said gas-inlet end of said drum, a frusto-conical section of substantial axial length having open ends one of which is larger than the other, the large end of said section being fixed to the inner periphery of said wall, and the small open end of said section having a cross-sectional area not more than one-third that of said chamber, said section forming a gas inlet chamber for said treating chamber, a gas reservoir chamber communicating with the small end of said section and associated therewith by a non-gas-tight eccentric-motion-permitting joint, means for supplying treating gas to said reservoir chamber under positive pressure to thereby supply gas under positive pressure to said gas inlet chamber and to said treating chamber, and means for discharging treated material from said treating chamber thru said gas inlet chamber while out of contact with a gas stream passing thru such inlet chamber.

2. Apparatus for treating solid material at least some of which exists as dust when in the treated condition, which apparatus comprises a rotary drum forming a treating chamber and having a material inlet-gas outlet end and an oppositely disposed material discharge-gas inlet end, means for introducing solid material to be treated into said material inlet end of said chamber, means for moving the material thru said chamber to said gas inlet end, an annular wall fixed at its outer periphery to said gas-inlet end of said drum, a frusto-conical section having open ends one of which is larger than the other, the large end of said section being fixed to the inner periphery of said wall and having a cross-sectional area not more than half that of said chamber, and the small open end of said section having a cross-sectional area not more than one-third that of said chamber, said section having an axial length equal to at least half the diameter of said small end and forming a gas inlet chamber for said treating chamber, a gas reservoir chamber communicating with the small end of said section and associated therewith by a non-gas-tight eccentric-motion-permitting joint, means for supplying treating gas to said reservoir chamber under positive pressure to thereby supply gas under positive pressure to said gas inlet chamber and to said treating chamber, and means for discharging treated material from said treating chamber thru said gas inlet chamber while out of contact with a gas stream passing thru such inlet chamber.

3. Apparatus for treating solid material at

least some of which exists as dust when in the treated condition, which apparatus comprises a rotary drum forming a treating chamber and having a material inlet-gas outlet end and an oppositely disposed material discharge-gas inlet end, means for introducing solid material to be treated into said material inlet end of said chamber, means for moving the material through said chamber to said gas inlet end, an annular wall fixed at its outer periphery to said gas-inlet end of said drum, said wall having a frusto-conical section of substantial axial length having open ends one of which is larger than the other, the large end of said section being relatively adjacent said gas inlet end of said drum and the small end of said section being relatively remote from said gas inlet end of said drum, the small open end of said section having a cross-sectional area not more than one-third that of said chamber, said section forming a gas inlet chamber for said treating chamber, a gas reservoir chamber communicating with the small end of said section and associated therewith by a non-gas-tight eccentric-motion-permitting joint, means for supplying treating gas to said reservoir chamber under positive pressure to thereby supply gas under positive pressure to said gas inlet chamber and to said treating chamber, and means for discharging treated material from said treating chamber while out of contact with a gas stream passing through such inlet chamber.
